CLAIM

The ornamental design for a garment as shown and described.

DESCRIPTION

FIG. 1 is a perspective view of a front and right side of a garment with an ornamental design applied to an external surface thereof, the garment disposed in a wear configuration;

FIG. 2 is a perspective view of a front and left side of the garment of FIG. 1;

FIG. 3 is a front elevational view of the garment of FIG. 1; FIG. 4 is a rear elevational view of the garment of FIG. 1; FIG. 5 is a right-side elevational view of the garment of FIG. 1;

FIG. 6 is a left-side elevational view of the garment of FIG. 1;

FIG. 7 is a top plan view of the garment of FIG. 1;

FIG. 8 is a bottom plan view of the garment of FIG. 1; FIG. 9 is a perspective view of a front and right side of another embodiment of a garment with an ornamental design applied to an internal and an external surface thereof, the garment disposed in a wear configuration and in a first, closed configuration;

FIG. 10 is a perspective view of a front and left side of the garment of FIG. 9;

FIG. 11 is a front elevational view of the garment of FIG. 9; FIG. 12 is a rear elevational view of the garment of FIG. 9; FIG. 13 is a right-side elevational view of the garment of FIG. 9;

FIG. 14 is a left-side elevational view of the garment of FIG. 9;

FIG. 15 is a top plan view of the garment of FIG. 9; FIG. 16 is a bottom plan view of the garment of FIG. 9; FIG. 17 is a front elevational view of the garment of FIG. 9 in a second, open configuration.

FIG. 18 is a perspective view of a front and right side of the garment of FIG. 9 in a third, reversed, closed configuration; FIG. 19 is a perspective view of a front and left side of the garment of FIG. 18;

FIG. 20 is a front elevational view of the garment of FIG. 18;

FIG. 21 is a rear elevational view of the garment of FIG. 18;

(Continued)

FIG. 22 is a right-side elevational view of the garment of FIG. 18;

FIG. 23 is a left-side elevational view of the garment of FIG. 18;

FIG. 24 is a top plan view of the garment of FIG. 18;

FIG. 25 is a bottom plan view of the garment of FIG. 18; and,

FIG. 26 is a front elevational view of the garment of FIG. 18 in a fourth, reversed, open configuration.

The dash-dash-dash lines illustrate portions of the article and form no part of the claimed design. The various surface treatments applied to the surfaces of the garments represent a contrast in appearance and do not illustrate any material, surface ornamentation, or surface decoration.

1 Claim, 20 Drawing Sheets
